ERNEST CLARK, OF ABINGTON, MASSACHUSETTS, ASSIGNOR TO ABINGTON TEXTILE MACHINERY WORKS, OF BOSTON, MASSACHUSETTS, A TRUST.

PNEUMATIC STRIPPER ATTACHMENT FOR CARDING ENGINES.

Application filed February 23, 1926. Serial No. 89,855.

The invention has relation, in general, to pneumatic stripper attachments such as are employed in connection with carding engines for removing accumulations of dirt, short fiber, etc., from among the teeth of the moving card-clothed surfaces of such machines. It is designed for application to stripper attachments of the class in which the stripping is effected through the employment of a nozzle that is caused to travel from one side of a machine to the other by a traverse-screw that is rotated by means of spur-gear-wheels from a convenient working part, usually the so-called doffer-gear.

More particularly, the invention relates to the means for rotating the traverse-screw of stripper attachments of the said class. It provides for securing the proper rate of travel of the nozzle relative to the speed of rotation of the doffer. It provides, further, for disconnecting the driving connections so as to permit the traverse-screw and nozzle to stand at rest.

Illustrative embodiments of the features of the invention are shown in the drawings. Fig. 1 of the drawings is a perspective view of certain portions of a carding engine and pneumatic stripper attachment including the said embodiments. The gear-box 6 is partly broken away in this view.

Fig. 2 is a sectional view of the gear-box of Fig. 1 and associated parts.

Fig. 3 is a somewhat similar view showing the gear-wheels disengaged to cause the traverse-screw and nozzle to stand at rest.

Fig. 4 is a detail view in vertical section on line 4, 4, of Fig. 3.

Fig. 5 is a detail view in section on line 5, 5, of Fig. 2.

Portions of the main cylinder and doffer of a carding engine are indicated at 1 and 2, Fig. 1, and at 3 is indicated a portion of a removable door which forms a part of the cylinder casing, the said door being located in the angle between the cylinder and doffer, just above the doffer. At 4 is indicated a portion of supporting frame-work at one end of the doffer, and at 5, Figs. 1 to 5, a portion of the guard enclosing the doffer-gear (part-

ly shown at 51). At 6 is a gear-box, resting 50 upon the doffer-gear guard, made fast thereto by screws 61, 61, engaged with front and rear feet of the gear-box. The gear-box 6 partially encloses the spur-gears 8 and 7 by means of which rotary motion is transmitted 55 from the doffer-gear to the traverse-screw 71, the latter enclosed within the stationary traverse-tube 9, and cooperating with the nozzle-carrier 10 to cause the said carriage to travel from one side of the carding engine 60 to the other side thereof, so as to traverse the cylinder-stripping nozzle 11 and doffer-stripping nozzle 12 along the peripheries of the cylinder and doffer, respectively, from end to end of the cylinder and doffer. Doffer gear 51 constitutes in the case of the illustrated organization an actuating gear for the parts to and including the traverse-screw.

The drawings hereof show at 13, Fig. 1, a so-called three-way piece, constituting 70 what may be termed a suction-box, which is mounted upon the stripper-carriage, and to which is attached one end of the suction-pipe 14, Figs. 1 and 6. To the said three-way piece or suction-box are attached the 75 two stripper nozzles, 11 and 12. The stripper nozzle 11 extends rearwardly from the three-way piece toward the cylinder, its induct-end or mouth being entered into a slot 31 in door 3, the said slot extending horizontally lengthwise of the cylinder, so that the 80 said end of the cylinder-nozzle works close to the face of the card-clothing of the cylinder. The stripper-nozzle 12 extends downward from the three-way piece alongside a 85 fixed bar 15, Figs. 1 and 6, extending lengthwise of the doffer, above the latter, the end of such nozzle working close to the face of the card-clothing of the doffer. This construction constitutes a combination nozzle 90 device which is adapted to strip both the cylinder and the doffer at the same time.

Traverse-tube 9 is mounted in parallelism with the card-clothed surfaces of the main cylinder 1 and doffer 2, respectively. Consequently, as the nozzle-carriage 10 travels across the width of the carding engine, the mouths of the two stripper-nozzles 11 and

12 move in paths which are parallel with such surfaces, the said surfaces being stripped progressively by the suction at the mouths of the respective nozzles.

6 The features and construction referred to thus far do not involve the invention, *per se*.

It is found advisable in practice that the rate at which the carriage and nozzles are traversed should be so related to the rate 10 of rotation of the doffer that the lateral movement of the carriage and nozzles during one revolution of the doffer shall be substantially equal in extent to the width of the mouth of the doffer-nozzle. This re-

lation is secured through a proper ratio between the number of teeth on motion-gear 7 on the end of traverse-screw 71 and the number of teeth on doffer-gear 51. In some cases it is found at the time of applying a stripper attachment to a carding engine that the doffer is rotated at such an excessive speed that a change of ratio is necessary, in order that the traverse-screw may not be rotated at too high a rate and

25 thereby traverse the carriage and nozzles at an excessive speed, so that the doffer-nozzle will not properly perform its work. This change of ratio is effected by replacing the motion-gear 7 by one having the requisite 30 different number of teeth. To provide for this replacement or change of the motion-gear, the latter is removably engaged with the traverse-screw shaft by means of one or more screws 72, Figs. 2 and 3. Replacement is necessary, also, when the doffer-nozzle first in use 35 is replaced by one having a mouth of different width. For instance, with a doffer-nozzle having a four-inch mouth, and a traverse-screw having a half-inch pitch, a traverse of four inches to every turn of the doffer would be given by means of a ratio of eight to one between the teeth of the doffer-gear 51 and those of the motion-gear 7. If a three-inch nozzle should be applied, the 40 ratio should be as six to one, to be attained by the substitution of a motion-gear 7 having a proportionately increased number of teeth. Replacement of motion-gear 7 is necessary in case a traverse-screw having a different pitch is substituted.

As is obviously true, the diameter of motion-gear 7 is in proportion to the number of teeth on such gear. Consequently adjustment of the idler-gear 8 must be effected 55 to suit the diameter of the substitute motion-gear. Accordingly, the gear 8 is mounted with capacity for such adjustment, through being supported by carrier-arms 81, 81, that are hung to the traverse-screw shaft at opposite sides of the motion-gear 7, and extend forwardly therefrom. The idler-gear 60 is mounted between such arms upon a cylindrical bushing 82, Fig. 5, which is held in place by means of a bolt 83 occupying slots 84 in the arms. The slotted carrier-arms

81, 81, constitute a slotted support for the idle-gear. The slots 84 extend in directions permitting the bolt, spacer-bushing and idler-gear to be adjusted to accommodate the diameter of the motion-gear 7 and keep the 70 teeth of the idler-gear properly engaged with those of the motion-gear 7. A head on one end of the bolt 83 makes contact with the outer side of one arm 81, and a nut on the screw-threaded other end of the bolt 75 makes contact with the outer side of the other arm, and when the said nut is tightened the bolt and spacer-bushing are clamped fixedly in position.

The slots 84 enable a larger or a smaller 80 motion-gear to be substituted to provide for a different ratio of speed between the doffer and the nozzle, with the same size idler-gear and without changing the size of the gear-box.

85 The carrier-arms 81, 81, constitute a support for the idler-gear 8 which is manually movable to enable such gear to be disengaged from doffer-gear 51 at will, or re-engaged therewith. Fig. 3 shows said arms lifted and the disengagement effected. As a convenient means of holding the gear 8 thus disengaged, a latch 86 is connected pivotally with the carrier-arms 81, 81. This latch constitutes a prop by means of which the arms and gear 8 may be held in lifted position. In Fig. 3 the lower end of the latch rests upon the forward foot of the gear-box, behind the head on the corresponding screw 61, such head being utilized 100 as a detent for the said end of the latch, to prevent slipping of the latch and undesired dropping of the carrier-arms 81, 81, and return of the idler-gear 8 into mesh with doffer-gear 51.

105 For convenience in manually operating the latch and raising or lowering the carrier-arms and idler-gear, the latch is furnished with a downwardly curved projection 87 adapted to serve as a finger-hold.

110 What is claimed as the invention is:—

1. In a pneumatic stripper attachment for carding engines, the combination with a stripper-nozzle, a traverse-screw, and an actuating gear, of a change-gear on said 115 traverse-screw, an idler-gear intermediate said actuating gear and said change-gear, and a slotted support providing for adjustment of the idler-gear to suit change-gears of different diameters.

120 2. In a pneumatic stripper attachment for carding engines, the combination with a stripper-nozzle, a traverse-screw, a gear thereon, and an actuating gear, of a swing- 125 ing idler-gear support hung concentrically with the traverse-screw and movable at will to disengage the idler-gear from the actuating gear and reengage it therewith, as desired, and means for adjusting said idler-gear relative to the other gears to suit 130

change-gears of various diameters applied to the traverse-screw.

3. In a pneumatic stripper attachment for carding engines, the combination with a stripper-nozzle, a traverse-screw, a change-gear, and an actuating gear, of a slotted swinging idler-gear support movable at will to disengage the idler-gear from the actuating gear and reengage it therewith, and a bolt on which said idler-gear is mounted, ¹⁰ adjustably applied to the slotted support to suit change-gears of various diameters.

ERNEST CLARK.
